UNITED STATES PATENT OFFICE

WALTER DOUGLAS LA MONT, OF LARCHMONT, NEW YORK, ASSIGNOR TO LA MONT CORPORATION, OF NEW YORK, N. Y., A CORPORATION OF NEW YORK

SHIELDED SUPERHEATER

Application filed April 26, 1928. Serial No. 272,873.

This invention relates to steam generating and superheating systems and its primary object is to attain a high efficiency in steam generation and superheating and, at the same time, insure that the superheater elements are at no time subjected to a temperature so high that they would be injured thereby. It is the general practice to use superheater tubes bent somewhat in the shape of a hair-
pin, the steam entering at one end and passing through the bent tube being discharged near the same end at which it enters. In boilers of locomotives such tubes are inserted within the fire tubes and while the steam flow through one arm of such a tube is in a direction counter to the flow of the hot gases through the fire tube, the steam flowing in the other arm of the superheater tube is in the same direction as the gas flow. It follows from this arrangement that the steam in the tube near the discharge end thereof is often at a temperature higher than the gases at this point so that some of the superheat of the steam is re-transferred to the gases and therefore wasted.

In the present invention the superheater tubes run straight through the fire tubes. Where such tubes are used in a locomotive or where used, for example, in an upright furnace, the steam to be superheated is introduced at the cooler end, the steam flowing in a direction counter to the gas flow. Under such conditions the gas temperature at the steam intake end of the super heater may never be lower than the temperature of the steam at that end and therefore no heat of the steam will be lost to the gases.

Heretofore, however, there has been difficulty in the use of superheater tubes having one end extending into or near the fire box, on account of the excessive heat to which they are subjected at this point and the danger of being injured by such heat. According to the arrangement of the present invention, where-
by La Mont tubes are extended lengthwise of the gas flow and among the superheater tubes, it becomes feasible to protect the superheater tubes' ends in the zone of the hottest gases and even in the zone of radiant heat, if such tubes are extended into such zone, by the

steam generating tubes and headers, such tubes and headers being extended beyond the ends of the superheater tubes in the hotter zone.

By using steam generating tubes operating upon the La Mont principle, that is to say where water is introduced into the tubes in quantity greater than their steam generating capacity, it is also possible to obtain the advantages of counterflow in the steam generating tubes as well as in the superheater tubes.

These and other features and advantages will be further set forth in the following description and claims and will be better understood in connection with the accompanying drawings, which show in more or less schematic form two practical embodiments of the invention.

Figure 1 is a longitudinal sectional view taken on the line 1—1 of Figure 2.

Figure 2 is a section on the line 2—2 of Figure 1, looking in the direction of the arrows in that figure.

Figure 3 is a perspective view showing one of the intake headers with parts broken away to show the jet orifices and tubes.

Figure 4 is a section on the broken section line 4—4 of Figure 1.

Figure 5 shows sections of two fire tubes with the steam generator and superheater elements therein.

Figure 6 is a view taken on the line 6—6 of Figure 1 but with the lower portion broken away to show parts beneath the boiler plate.

Figure 7 is a cross section of a fire tube showing one way of supporting the steam generating tubes therein.

Figure 8 is a longitudinal section of a portion of a fire tube showing the supporting bracket of Figure 7 in elevation, and

Figure 9 is an assembly view of a vertical furnace embodying the invention.

Referring to the drawings, Figure 1 represents the boiler of a locomotive having a steam space 1, a fire box 1—a, a front gas space 1—b and a smoke stack 1—c.

Leading out from the water space of the boiler is a water pipe 2, Figures 1 and 2, which connects with the suction side of a pump 3, preferably of the centrifugal type.

A conduit 4 leads from the discharge side of the pump through a strainer 5 and connection 6 to a distributing manifold 8 through which water is supplied to a plurality of 5 steam generating intake headers 9, each of which is suitably connected to the manifold in a manner well known in the art.

Each header 9 is disposed vertically in the gas space 1—*b* and adjacent a vertical row of 10 fire tube ends, the fire tubes being indicated by the reference character 12. Suitably fitting into each header are steam generating elements 10, several of these being shown in Figure 3, wherein is also shown the jet orifices 11, by which the water supplied under pressure from the pump is distributed to the several elements connected to an individual header.

The elements 10 are small in diameter as 20 compared with the diameter of a fire tube so that several may lie alongside each other throughout the length of a single tube. Four tubes 10 are shown in one fire tube in Figure 5 right hand view, and also in Figure 7. As 25 shown in Figure 1 the elements 10 extend beyond the fire box end of the fire tubes a distance which, in practice, is approximately 21 inches, where they enter discharge headers 14, Figures 1 and 6. These headers are closed 30 at their lower ends but their upper ends pass through the boiler plate 15 and terminate at its upper surface.

The amount of water supplied by the pump through the jet orifices in the intake headers, 35 is in quantity greater than the evaporating capacity of the tubes or elements 10.

The conditions as to size of the steam generating elements, the velocity of flow and size of the jet orifices in order to continuously 40 propagate a film of water along any tube, have been described in full in my co-pending application Serial No. 209,024, filed July 28, 1927. As disclosed therein, the size of the steam generating tubes suitable to effect generation of steam according to the method disclosed in said application may be about $5/8$ inch diameter, although tubes of somewhat larger or smaller diameters may be used. 45 Without going into the details of all the factors involved it is sufficient for the purpose of the present invention to emphasize the fact that steam and water flow along the steam generating elements from the intake headers 9 and excess water is delivered to the discharge headers and this fact is availed of in the present invention to afford protection to the superheaters and superheater elements.

Steam from the boiler passes through an outlet connection 16 to the superheater manifold 17, shown in Figures 1 and 2. This manifold is in the form of a cylinder very similar to the manifold 8 for the steam generating elements but somewhat larger. The superheater intake headers 19 may be similar in construction to the water intake headers 9,

as shown in Figure 3. Each header 19 is connected with the manifold 17 by a nipple 18 and extends vertically in front of the ends of a series of fire tubes.

Leading from each superheater header is a plurality of superheater tubes 20. These may be larger than the generating elements 10, as will be noted from Figures 2 and 5, but not necessarily so. In some cases two superheater elements may run through a single fire tube as shown.

In Figure 2 of the drawings it will be noted that the superheater tubes may pass through fire tubes adjacent to those through which the steam generating elements pass but this alternate arrangement of steam generating tubes and superheated tubes is not a necessary arrangement since the number of superheater tubes would depend upon a number of conditions well known in the art, so that the arrangement shown, is merely illustrative of one embodiment of the invention and in no sense limits it to the exact construction shown.

The opposite end of each superheater tube extends into a discharge header 21, shown in elevation in Figure 1 and in section in Figure 6. Each of the headers 21 leads to a steam collecting pot 22, Figure 1, from which steam is taken to the cylinders of the locomotive or to any other point where it is to be used.

Nipples 21—*a* are arranged between the pot 22 and each discharge header 21, or other suitable connections might be provided.

For convenience the intake headers 19 are situated between the intake headers 9 and the front boiler plate 19—*a* and are spaced from the latter a distance at least equal to the distance between the discharge headers 14 and 21. This construction enables any set of tubes 20 to be moved forwardly to bring the 105 headers 21 sufficiently close to the headers 14 to permit access to the former.

The nipples 21—*a* would, of course, have to be cut to permit this movement.

As already stated, an object of the invention is to protect the superheater headers and the ends of the superheater tubes themselves from too high a temperature, whether this be due to radiant heat in the fire box or to the high temperature gases entering at the fire box end of the fire tubes. The invention also provides an arrangement of superheater elements so that the heat of the gases is most efficiently utilized in superheating the steam. Therefore the steam generating elements 10 extend beyond the fire tubes and into the fire box some distance beyond the superheater headers 21 so that the latter and the ends of the superheater tubes are within the radiant shadow of the steam generating headers and tubes. Furthermore, the hot gases are in contact with the steam generating headers and tubes 10 for a sufficient length of time to effect a considerable reduction in the temperature of such gases before they come into con-

tact with the superheater headers and superheater elements so that said headers and elements are in no danger of being burned out.

Whereas I have mentioned 21 inches as a suitable distance for extending the steam generating elements beyond the fire tubes this is not to be understood as limiting this distance to the figure stated as the distance will be varied to suit different conditions.

10 It is to be particularly noted that the steam generating portion of the elements 10 in the fire box end of the locomotive are being constantly supplied with water, and some water is discharged into the headers 14. Therefore, 15 these headers and the tubes adjacent thereto will very rapidly absorb heat from the fire and from the gases, and such gases will be quickly lowered in temperature in passing over these headers and tubes.

20 The gases flow from the left to the right in Figure 1 through the fire tubes. With the arrangement shown, however, the water for the steam generating elements is introduced into the headers 9 and flows in a direction 25 counter to that of the gases. The steam to be superheated likewise enters the headers 19 and flows counter to the direction of the gases. It results from this arrangement of counter-flow that the temperature of the steam at or 30 near the headers 19 is always at or below the temperature of the gases at that point.

In Figure 7 an arrangement for suitably supporting the steam generating elements within a fire tube is shown. For this 35 purpose a bracket 25 holds the four tubes in place assisted by a spacer 25—a of suitable shape.

In prior constructions there has been, as far as known to me, no way of attaining 40 completely the advantages of counterflow of steam in the superheater elements, because such an arrangement would necessitate the placement of the superheater headers in or near the fire box where they are necessarily 45 exposed to temperatures greater than they can withstand for long life and low upkeep. With the present arrangement, however, the steam generating elements and headers afford the necessary protection while preserving 50 the advantages of the counterflow arrangement.

In Figure 9, the principle of the invention is illustrated in a slightly different form of apparatus. Here the steam generating elements and superheater elements are arranged 55 in a vertical direction instead of horizontal.

26 represents the lower walls of a supporting structure and 28 the upper walls thereof. The general principle and mode of operation, 60 however, is the same as in the first described form of invention.

A pump 29 is provided which forces water through a pipe 30 to the distributing manifold 31. Leading out from this manifold is 65 a plurality of intake headers 32 shown in

cross section in Figure 9. These headers, however, may be like those shown in Figure 3 and from each of which leads a plurality of steam generating elements 33, which elements extend vertically or approximately so, to 70 lower or discharge headers 34, the latter connected to a discharge manifold 35 from which the steam and any excess water flows to the steam and water collecting pot 36, where the steam and water are separated, the steam 75 passing to a steam conduit 37 while the excess water flows back to the pump through the water conduit 38.

A feed water pipe 39 supplies water to take the place of that evaporated. The steam from the pot 36 after passing through the conduit 37 enters the separator 41 and any water that may be entrained in the steam is separated and falls into the collector 42, from which a water return connection 43 leads 85 back to the pot 36. The steam passes up through the steam conduit 44 to the superheater distributing manifold 45, thence by connections 46 and branches 47 to the several intake headers 48 for the superheaters. 90 From these headers the superheater elements 49 lead to lower superheater discharge headers 50, the steam passing thence through branch pipes 51, connections 52, to the superheater discharge manifold 53 from which it 95 is lead by a steam conduit 54 to the place of use.

A water level control shown diagrammatically at 56 maintains the water level in the collecting pot 36 through suitable connections 57 acting on the valve 58 in the feed water supply pipe 39.

As in the first described form of the invention the steam generating headers and the lower ends of the steam generating tubes extend such distances below the ends of the superheater tubes and headers that the latter are amply protected from the radiant heat and high temperature gases in the lower portion of the boiler. The same advantages of 105 counterflow are availed of in this form of the invention as have been set forth fully in describing the first form. The gases enter the furnace near the bottom which may also be a zone of radiant heat, the gases passing in the direction of the arrows up through the space between the steam generating and superheater elements, where they pass out through a stack near the top (not shown).

110 What is claimed as new is:

1. In a steam generator and superheater system, steam generating elements situated in the path of the heating gases and arranged to absorb heat by convection, superheater elements situated among the steam generating elements, intake and discharge headers for said steam generating elements and superheater elements, and means for supplying and distributing water to the steam generating elements through their intake headers in 115 120 125 130

- quantity greater than the steam generating capacity of the elements whereby excess water enters the discharge headers, the intake headers of both the steam generating elements and superheater elements being located at the ends of the respective elements remote from the zone of hottest gases, whereby the flow of fluid through both the steam generating elements and superheater elements is counter to the direction of flow of the heating gases, the discharge headers for the steam generating elements being located such distances beyond the discharge headers for the superheater elements that the gases are cooled by contact with the steam generating discharge headers and the steam generating elements before coming into contact with the superheater elements and superheater headers.
2. In combination with a boiler having fire tubes and a firebox, a set of steam generating elements extending through some of said fire tubes and a set of superheater elements extending through some of said fire tubes, headers situated beyond the fire tubes at each end thereof to which a set of steam generating elements and a set of superheater elements are respectively connected, means for introducing water through the headers into one end of each of the steam generating elements in quantity greater than the steam generating capacity of the elements, whereby steam and water are discharged into the headers at the other end of the sets of elements, and means for introducing steam into the superheater elements through the headers remote from the fire box whereby the steam flows counter to the flow of heating gases, the steam generating elements and headers at the fire box end extending such a distance beyond the superheater elements and headers that the superheater elements and headers are shielded from contact with gases at too high a temperature.
3. In combination with a boiler having fire tubes and a fire box, a set of steam generating elements extending through some of the fire tubes and a set of superheater elements also extending through some of said fire tubes, means for introducing water into the steam generating elements, and means for introducing steam into the superheater elements at their ends remote from the fire box whereby the steam flows counter to the flow of the heating gases, the steam generating elements at the fire box end extending beyond the superheater elements thereby shielding them from contact with gases at too high a temperature.
4. In combination with a boiler having fire tubes and a fire box, a set of steam generating elements extending through some of the fire tubes and a set of superheater elements also extending through some of the fire tubes, means for introducing water at the end of the

steam generating elements remote from the fire box in quantity in excess of the steam generating capacity of the elements and discharging the excess water at the fire box end of said elements, and means for introducing steam into the superheater elements at their ends remote from the fire box whereby the steam flows counter to the flow of the heating gases, the steam generating elements at the fire box end extending beyond the superheater elements thereby shielding them from too high a heat.

5. In a steam generator and superheater system, steam generating elements situated in the path of the heating gases to absorb heat by convection and extending into a zone of radiant heat, superheater elements situated among the steam generating elements and having portions thereof extending into the radiant heat zone, a header in the radiant heat zone and situated among the steam generating elements to which the superheating elements are connected as a set, and means for introducing steam into the superheater elements in counterflow to the heating gases, the arrangement of the superheater elements and the header in relation to the steam generator elements in the radiant heat zone being such that the superheater elements and the header are situated within the radiant shadow of the steam generating elements.

6. In a steam generator and superheater system, steam generating elements of relatively small cross section situated in the path of the heating gases to absorb heat by convection, superheater elements situated among the steam generating elements, means for positively delivering and distributing the water to the heat absorbing surfaces of the steam generating elements and causing it to flow counter to the flow of the heating gases, and means for introducing steam into said superheater elements so that its direction of flow therethrough is counter to that of the flow of the heating gases, a portion of the system generating elements being situated beyond the ends of the superheater elements in the direction of the higher heat so that by reason of the absorption of heat by the steam generating elements the gases are cooled to a temperature insufficient to cause damage to the superheater elements.

7. In a steam generator and superheater system, sets of steam generating elements situated in the path of the heating gases and arranged to absorb heat by convection, superheater elements providing steam superheating surface and so situated among the sets of steam generating elements that a set of steam generating elements is adjacent to a portion of the superheating surface which is in the zone of high temperature, each of the sets having an individual inlet and outlet, and means for introducing steam into said superheater elements so that its direction of flow through

- said elements is counter to that of the flow of the heating gases, said steam generating elements extending beyond the superheater surface in a direction counter to the flow of
5 the heating gases for such a distance that the gases are cooled by reason of the absorption of heat by the generating elements to a temperature insufficient to cause damage to the superheater elements.
10 8. In a steam generator and superheater system, steam generating elements of relatively small cross section and superheater elements situated in the path of the heating gases and arranged to absorb heat by convection, means to positively force water into said generating elements in quantity greater than their evaporating capacity and causing it to flow in a direction counter to the flow of the heating gases, and means for introducing
15 steam into said superheater elements, said steam generating elements having at least a portion located beyond the ends of the superheater elements in a direction counter to the flow of the heating gases, whereby the gases
20 are cooled by reason of the absorption of heat by the generating elements to a temperature insufficient to cause damage to the superheater elements.
